UNITED STATES PATENT OFFICE.

JAMES B. PHILLIPS, OF NEW YORK, N. Y.

BUSTLE.

SPECIFICATION forming part of Letters Patent No. 295,584, dated March 25, 1884.

Application filed January 10, 1884. (No model.)

To all whom it may concern:

Be it known that I, JAMES B. PHILLIPS, of New York city, in the county and State of New York, have invented certain new and useful Improvements in Stiffeners for Bustles or other Articles of Wearing-Apparel, of which the following is a specification.

My improvements apply to that class of stiffeners or springs in bustles or other articles of wearing-apparel which are provided with a series of parallel pockets inclosing springs, which extend from side to side, and are held in a more or less bent condition by means of lacings, which extend across and connect the edges, and may be adjusted in tightness so as to give any desired degree of fullness to the bustle. I have conceived and practically wrought out important improvements in the springs.

20 The following is a description of what I consider the best means of carrying out the invention.

I sew together, by hand or by any suitable machine, three coarse braids of straw. I can use successfully Dunstable, Milan, or Canton straw. I prefer to use what is known as the "Davis sewing-machine," or the "Palmer straw-sewing machine." The thread is preferably coarse, and applied with only moderate tension. Around this aggregation of straw braids I wind, at one or more operations, a sufficiently thick envelope of cotton-batting or other unwoven fibrous material to give an approximately smooth and even surface. The material of the bustle being sewed together, except that one side is left open, exposing all the pockets to receive the springs, and the partially-made construction being laid flat on the work-table, a metal funnel is introduced successively in the open end of each pocket, and one of the compound soft-covered springs is easily entered through the aperture thus held open and thrust in until its end meets the further end of the pocket. Then 45 the spring is cut off, and, taking care to have the soft envelope snugly compressed on the straw at the entering end, the funnel is changed to the next pocket and the operation repeated. Then a line of stitching up and down the side 50 closes all the pockets, and on applying the lacings and drawing the edges toward each

other to the proper extent and tying the lacings the bustle is complete.

The accompanying drawings form a part of this specification.

Figure 1 is an elevation showing the inner face; Fig. 2, a vertical section, slightly in perspective. Fig. 3 is a cross-section of the springs which are inserted in the pockets. It is on a larger scale than Fig. 2. Fig. 4 is a corresponding cross-section through the braid alone. Fig. 5 shows a modification in which only a single strand of straw braid is employed. Fig. 6 is a section through the metal funnel which I introduce in the several pockets successively 65 to facilitate the introduction of my peculiar bat-covered springs.

Similar letters of reference indicate corresponding parts in all the figures.

A B C are three braids of Dunstable straw— 70 one upon the other—the middle one being preferably the widest.

D is the line of confining-stitches, and E the envelope of cotton-batting. The latter is wound so that the fiber extends around rather 75 than longitudinally of the spring.

G is the exterior of the bustle. It is formed of two or other number of pieces of silesia or other suitable fabric cut and applied together so as to give the desired swell in the vertical 80 line. G' is the corresponding inner fabric. These are joined by lines of stitching g, extending from side to side. I place two lines of stitching g' near together. They define the narrow portions of the fabric of the bustle, 85 which are not distended by the springs. The wider spaces g' form pockets extending continuously across from one side of the bustle to the other.

H is the lacing rove through eyelets J in 90 narrow pieces of fabric I, which extend up and down on each edge of the bustle, and are secured by a line of stitching, i.

In applying the parts together, when the lines of stitching g are produced and the binding I' is secured on one side, the spaces between the two fabrics G and G' are ready to serve as pockets, being opened at the unsewed side. M M' is the funnel, the rounded flange M' lying outside, and the body M lying within 95 the mouth of the pocket when in position for use. After my compound spring has been 100

inserted and cut off at the proper length in each pocket, the binding I' is sewed on the opposite edge, thus closing the pockets g'. A lacing, H, will usually be inserted and secured with the proper tension after the other portions of the work are completed.

My lacings H are of what is known as "elastic"—a core of soft vulcanized rubber covered with cotton, silk, or other fibrous material braided on. The combined effect of my springs A B C D E in the body G G' and of the elastic lacing H gives a yielding and yet persistent form, which is easy for the wearer and highly advantageous.

I can use more than three of the braids, or two may serve successfully. The cotton-batting may be applied in a sufficiently thick bat wound only once around, with a slight overlap; or it may be wound on spirally or otherwise in a very thin layer, so that ten or other considerable numbers will be applied to produce the desired thickness. The thickness of the cotton may be varied. Other material than cotton—as coarse wool—may serve. I prefer cotton, as my experiments indicate that it maintains its position in the act of inserting the springs, and serves well in insuring a smoothly rounded appearance in the several distended pockets when the construction is complete and ready for use. The covering may serve with some success largely intermingled with shoddy. A single straw braid made of proper size and of a round or approximately round form may serve with some success, instead of the three shown. Fig. 5 is a cross-section of one of the springs made in that

manner by a single braid with the bat of fiber wound on as a covering in the same manner as it is wound on in what I esteem the preferable form. (Shown in Figs. 2 and 3.)

40

I believe that other straw than Dunstable, Milan, or Canton may be used. Mixtures of different straws may be used without serious disadvantage.

It will be readily understood that the bending of the bustle after the pockets are filled tends to contract and wrinkle those faces of the pockets which are presented on the inner side of the bustle next to the person; but the exterior is eminently smooth and faultless in 50 appearance.

I claim as my invention—

1. As a new article of manufacture, a spring or stiffener for wearing-apparel, consisting of straw braids, one upon the other, the braids being bound together and enveloped in a covering of unwoven fibrous material, substantially as set forth.

2. In combination with a bustle, a spring consisting of straw braids, one upon the other, the braids being united by stitches D and enveloped in a covering of cotton-batting, substantially as shown and described, for the purpose set forth.

In testimony whereof I have hereunto set 65 my hand, at New York city, New York, this 8th day of January, 1884, in the presence of two subscribing witnesses.

JAMES B. PHILLIPS.
